(57) **CLAIM**

The ornamental design for an electrical plug, as shown and
described.

DESCRIPTION

FIG. 1 is a left elevation view of an electrical plug showing
our new design;

FIG. 2 is a right elevation view thereof;

FIG. 3 is a top view thereof;

FIG. 4 is a bottom view thereof;

FIG. 5 is a front view thereof;

FIG. 6 is a rear view thereof;

FIG. 7 is a bottom left perspective view thereof; and,

FIG. 8 is a top left perspective view thereof.

The structural features depicted by broken lines have been
shown for the purpose of illustrating portions of the elec-
trical plug that form no part of the claimed design.

1 Claim, 3 Drawing Sheets
